AUTOMATIC CONTROL FOR RADIO RECEIVERS

Robert C. Avery, Sunnyside, Long Island, N. Y.

Application September 20, 1933, Serial No. 690,198

2 Claims. (Cl. 250—20)

This invention relates to an automatic control for radio receivers.

One of the main objects of the invention resides in a means by which the programs of selected radio broadcasting stations may be successively brought into a radio receiver at various predetermined timed intervals. For example, the apparatus may be set to receive a varied evening's program sent out through different radio broadcasting stations, the apparatus serving to automatically tune the various stations in and out at predetermined times to receive the desired scheduled programs.

Another feature of the invention is to provide an automatic selective time control apparatus which may be associated with a radio receiver without interfering with the manual control of the receiver should it be desired to operate the same manually or independently of the automatic apparatus.

A further feature of the invention is the provision of an automatic selective time control apparatus wherein the selected stations may be tuned in and out more than once on each setting of the apparatus.

A still further feature is to provide an automatic selective time control apparatus which may be associated with various types of radio receivers now in use without requiring any changes in the circuits of the receiver, which is simple and inexpensive of manufacture, and which is positive and accurate of operation.

With these and other objects in view, the invention resides in the certain novel construction, combination and arrangement of parts, the essential features of which are hereinafter fully described, are particularly pointed out in the appended claims, and are illustrated in the accompanying drawings, in which:

40 Figure 1 is a fragmentary front elevational view of a radio receiver with my invention embodied therein.

Figure 2 is a detail sectional front elevational view of the time control clock.

45 Figure 2a is an enlarged detail vertical sectional view on the line A—A of Figure 2.

Figure 3 is a detail vertical transverse sectional view on the line 3—3 of Figure 1.

50 Figure 4 is a vertical transverse sectional view on the line 4—4 of Figure 3.

Figure 5 is a vertical transverse sectional view on the line 5—5 of Figure 3.

55 Figure 6 is a detail sectional perspective view of one of the station control switches,

Figures 7 and 7a are diagrammatic views of the electric control circuits.

Referring to the drawings by reference characters, the numeral 10 designates a radio receiver including a cabinet 11 of any conventional design within which the tuning shaft 12 is journaled. The front end of the shaft 12 extends beyond the front panel 13 of the cabinet, and carries a manipulating knob 14. A pointer 15 is fixed to the shaft 12 behind the panel 13 and traverses an arcuate shaped dial 16 visible through a similar shaped opening 17 in the front panel 13. The dial is marked to indicate meters indicative of broadcasting wave lengths. Although not shown in the drawings, the shaft 12 upon rotation controls the setting of the tuning instruments of the radio receiver. Also operable from the exterior of the front panel 13 is a toggle switch 17 and a volume control knob 18. The parts just described are common in the present type of radio receivers, and have been shown to illustrate the operation of my invention with respect thereto, and which invention will now be described.

Set in the front panel 13 is a clock 19, which may be either mechanically or electrically operated and which includes an arbor shaft 20 on which a second hand 21 is mounted, a tubular shaft 22 telescoping the shaft 20 and insulated therefrom by a sleeve 23 of dielectric material, while a tubular shaft 24 telescopes the shaft 22 and is in electrical contact therewith. A minute hand 25 is fixed to the shaft 22 while an hour hand 26 is fixed to the shaft 24. The second hand 21 is the longest of the three hands and the hour hand 26 is shortest, while the minute hand is of an intermediate length for a purpose to be presently explained. The hands 21, 25 and 26 all traverse the face of a clock dial 27 containing the standard twelve hours, but a twenty-four hour clock might be used if desired, but is not necessary for the general use to which the invention is put. The clock dial 27 beyond the clock face thereof is provided with an arcuate series of spaced electric contacts 28 adapted to be successively engaged by the hour hand 26 during rotation thereof. Although the contacts 28 have been shown in the drawings as extending between six and twelve o'clock, the same may extend entirely about the dial for operation over a twelve hour period instead of six hours. There are three equidistantly spaced contacts 28 between each adjacent pair of hour contacts 28, the spaces between two adjacent contacts is traversed by the

hour hand during a fifteen minute period of travel.

The dial 27 is also provided with four equidistantly spaced electric contacts 29 disposed beyond the circumferential plane of the contacts 28 and respectively disposed adjacent the hours numbered 3, 6, 9 and 12. The contacts 29 are disposed in the path of rotation of the minute hand 25.

10 An arcuate shaped contact member 30 is provided on the dial 27 beyond the circumferential plane of the contacts 29, a portion of which extends beyond the opposite sides of the radial plane of the hour designating 12 o'clock. However, a longer portion of the contact 30 extends to the right or clock-wise side of the hour 12 than to the left or counter-clockwise side thereof for a purpose to be hereinafter explained. The contact 30 is disposed in the path of rotation of the second hand 21 to be engaged thereby on each revolution of the same.

15 The four contacts 29 and the arcuate contact 30 are connected by wiring 31 as seen in Figure 7 of the drawings, and which constitutes part 25 of the time controlling circuit to be hereinafter fully described.

20 The clock 19 controls the operation of certain selected operating circuits together with the motor circuit for controlling the operation of an electric motor 32 of the reversible driving type. The motor 32 is employed for turning the tuning shaft 12 in either direction of rotation, and is mounted within the cabinet 11. The armature 33 of the motor carries a pinion gear 34 which is in driving engagement with a gear 35 frictionally mounted upon the tuning shaft 12 as seen best in Figures 3 and 5. The hub of the gear 35 is provided with a split friction collar 36, the split ends of the collar being under the tension of a spring 37, the tension of which may be adjusted by a set screw 38. Thrust collars 39 are mounted on the shaft 12 on opposite sides of the gear 35 to restrict longitudinal movement of the gear upon said shaft. The friction between the gear 35 and the shaft 12 is sufficient to enable the shaft to be driven by the motor 32 during automatic operation of the apparatus, while the resistance set up by the gear 35, pinion 34 and motor 32 overcomes the friction during the manual turning of the knob 14 when it is desired to manually tune the instrument of the radio receiver. A spring pawl 40 mounted on a fixed part of the cabinet engages the periphery of the gear 35 to prevent overriding of the gear during rotation of the same by the motor 32, to cause the gear and shaft to stop instantly upon the shutting off of current to the motor 32.

25 Fixed to the shaft 12 adjacent the gear 35 is a motor circuit selector member 41 by which the directional flow of current to the armature 33 of the motor 32 may be selectively controlled to rotate the motor 32 in opposite directions. The member 41 comprises a disk 42 of dielectric material, the center of which has a metallic bearing 43 which is fixed to the shaft 12. Countersunk in the outer periphery of the disk 42 are two semi-circular or arcuated shaped contacts 44 and 45, the adjacent ends of which are insulated apart as at 46. An arcuate shaped rail 47 of dielectric material is mounted upon a fixed support 48 and the curvature of the rail is struck on the axis of the disk 42 but on a plane beyond the same as seen in Figure 4. The support 48 is at the ends of the rail and the

said rail is disposed above and to one side of the top of the disk 42. The support 48 carries electric spring brush contacts 49 and 50 which engage the respective contacts 44 and 45 of the disk. Mounted on the rail 47 are station selector contact members 51, there being one for each radio station whose program is to be received by the setting of the apparatus. Each member 51 comprises a body 52 having a slot therein for the passage of the rail 47 and a set 10 screw 53 for securing the body in a fixed position along the rail. A spring contact 54 extends from the body 52 and the free end terminates in an angular finger 55 which has bearing contact with the periphery of the selector member 41. The selector contact members 51 are so positioned upon the rail 47 that when the fingers 55 of the same respectively engage a break 46 between the contacts 44 and 45, the tuning shaft 12 is in tuning position for the respective 20 broadcasting station. It will be understood that after once adjusting the selector contact members 51 upon the rail 47 for the tuning in of stations of various wave lengths, they need not be disturbed unless the stations alter their wave 25 length, or it is desired to set the contact members for other stations on different wave lengths.

25 Mounted on the panel 13 are selective time setting switches 56 for the respective radio broadcasting stations under control by the automatic apparatus. In the present instance, five different switches 56 are provided for controlling the time period of reception of five different radio broadcasting stations, for example WMCA, WEAF; WOR; WJZ, and WABC, and the same 35 are so marked to identify them. The switches 56 are arranged in a horizontal row across the front panel 13 and two separate rows have been shown in order that the same station may be tuned in twice without necessitating the re-setting of the switches, and if desired, more than two switches for each station may be provided should it be desired to preset the same station more than twice, as it is only necessary to arrange the time controlling contacts of like stations 40 switches in parallel.

30 A description of one station time switch 56 will be set forth as they are all alike, and a description of one will suffice for the others. Each switch 56 includes a shaft 57 journaled 50 in the panel 13 and in a spaced inner panel 58 as seen in Figure 6 of the drawings. The outer end of the shaft 57 has a knob 59 fixed thereto on which the radio station letters are provided and which knob has an annular flange 60 containing a radio indicating mark 61 extending inwardly from the periphery thereof. The mark 61 is adapted to coact with radio markings on a dial 62 provided on the exterior of the panel 13 and which indicates the hours from 6 to 12 60 o'clock, and the fifteen minute periods between the respective hours. Fixed to the shaft 57 and disposed adjacent the panel 58 is a switch arm 63, the free end of which is adapted to pass over a series of spaced annular arranged 65 contacts 64 which correspond in number to the number of fifteen minute periods between 6 and 12 o'clock or to the number of contacts 28 over which the hour hand 26 of the clock passes. A reset contact 65 is disposed beyond the twelve 70 o'clock contact 64 while interposed between the contact 65 and the adjacent end contact 64 is a flat spring 66 in the path of movement of the switch arm 63 which serves to move the switch arm to a neutral position after the arm 75

63 has been moved into engagement with the reset contact 65 for a purpose to be hereinafter described.

Stop pins 67 extend outwardly from the panel 58 to limit the turning movement of the switch arm 63 in opposite directions. It will be seen that by manually turning the knob 59, the switch arm 63 may be set to engage any selected time control contact 64; or the same may be turned to cause the switch arm to engage the reset contact 65, but when released, the contact arm is moved to a neutral position by the spring 66.

By reference to Figures 7 and 7^a, it will be seen that the contacts 64 of a particular station switch 56 are respectively connected to like contacts 64 of the other station switch 56 which controls the same station and which connection is made by wires 68 so that the contacts of like station switches are arranged in parallel while the wires 68 are respectively connected to a series of feeding wires 69 as at 70. The contacts 64 of all the station switches are respectively connected to the common feed wire 69, although only those wires 68 from the switches controlling station WOR are shown to avoid confusion by a repetition of a similar circuit.

Wires 71 lead from the fifteen minute contacts 28 to the respective feed wires 69 to form part of the time controlled circuits in which the station selector switches are arranged.

The switch arms 63 of the pairs of like station switches 56 are respectively connected by wires 72 to the respective control switch members 51.

The reset controls 65 of each row of switches 56 are connected together by branch wires 73 which connect with a common feed wire 74.

The start and stop switches 75 and 76 respectively are substantially the same in construction as the station control switches 56 with the exception of the spring 66 and a description of one of the switches 75 and 76 will suffice for the others. Each switch 75 and 76 includes a turnable switch arm 77 movable over a series of contacts 78 corresponding in number to the station switch contacts 64 and the contacts 78 of the start switch 75 are connected by wires 79 to corresponding contacts of the stop switch 76. The wires 79 are in turn respectively connected to the wires 69 as at 80. A knob 81 is fixed to the shaft on which the switch arm 77 is mounted and is provided with a radial indicating marker 82 which coacts with an hour dial 83 on the panel 13. The dial reads from 6 to 12 with fifteen minute designations between the hours. When the knobs 81 are turned to their limits, the indicating marker 82 registers with notations "on" and "off" associated with the start and stop switches 75 and 76 respectively. When in such position the switch arms 77 engage contacts 84 which are connected to the wires 74 by branch wires 85 placing them in parallel with the station switches 56.

The switch arm 77 of the "start" switch 75 is connected to an electromagnet 86 by a wire 87 which when engaged, moves the toggle switch 17 to "on" or "start" position. A magnet 88 is mounted opposite the magnet 86 and is connected by a wire 89 leading to the switch arm 77 of the stop switch 76. When engaged, the magnet operates the switch 17 to an "off" or "stop" position. Although the switch 17 is electromagnetically controlled, the same may be manually actuated when the automatic time

control apparatus is not in use in order to turn the radio receiver "on" or "off" as desired.

The automatic apparatus is operated from an electric supply, and the positive and negative leads therefrom are designated at 90 and 91 respectively in Figure 7 of the drawings. The diagrammatic wiring hereinbefore described and the further description of the same which now follows will be more clearly understood by placing the sheet containing Figure 7^a just below the sheet containing Figure 7 and lining up the lines which extend from one sheet to the other.

The positive or plug lead 90 from the source of energy is joined by a wire 92 which leads to the radio receiving set and joined thereto are wires 93 and 94 connected in turn to the respective electromagnets 88 and 86 and which form the positive sides of the circuits in which the electromagnets are arranged.

The negative lead 91 connects with the arbor shaft 20 on which the second hand 21 is mounted, and arranged therein is a switch 95 operable under the influence of an electromagnet 98 arranged in the stop circuit and which when energized serves to move the switch to open position. The switch 95 is manually operable to a normal closed position, and is under the light tension of a spring operating against action of the electromagnet.

The negative side of the time control circuits passes through the hands and contacts of the time control clock 19, while a branch wire 96 leads from the negative lead wire 91 and joins the wires 74, which wires are joined to the respective contacts 65 by the branch wires 13. A wire 97 leads from the wire 74 in Figure 7^a to the switch arm 98 of the toggle switch 17 and from there it leads to the negative side of the radio receiving circuit.

The motor 32 is of the reversing type whereby the armature may be driven in either direction depending upon the radial position of the gap 46 with respect to the contact fingers 54 when the station selector circuits in which the contact fingers are arranged are closed. For reversing the direction of the current to the armature 33 of the motor, while the directional flow of current to the field 99 of the motor remains the same, I employ a pair of relay operated reversing circuits, the relays being designated R and S. The relay R when energized operates a pair of switch arms 100 and 101 which are connected by wires 102 and 103 respectively with opposite sides of the armature 33. A wire 104 leads from the contact 49 to the winding of the relay and from there it joins a wire 105 leading from the negative side of the field 99 and terminating in a contact disposed in the path of inward swinging movement of the relay contact member 100. The relay contact member 101 is operated by the coil of the relay R to engage the terminal end of wire 106 joined to a wire 107 leading from the positive wire 92 to the positive side of the field 99.

The contact 50 is engageable with the contact 45 of the disk 42, and has one end of a wire 108 joined thereto while the said wire leads to the windings of the relay S and joins 105. Wires 109 and 110 lead from switch members 111 and 112 respectively, and which switch members are under the influence of the coil of the relay S. The ends of the wires 109 and 110 terminate in terminals disposed in the path of outward movement of the switch arms 100 and 101 of the relay R and are engaged thereby when the re-

lay R is deenergized. A wire loop 113 has its ends disposed in the path of outward movement of the switch members 111 and 112 and engage the same when the relay S is deenergized. When the relay S is energized, the switch member 111 engages the terminal end of a wire 114 which connects with wire 108, while the switch member 112 engages the terminal end of a wire 115 joined to the wire 105.

10 The operation of the device will now be described and for example the apparatus will be set to tune in station WOR at 6 o'clock, then switch to tune in the program from WJZ at 7 o'clock, and then return to station WOR at 8 o'clock and shut off the radio receiver at 9 o'clock. Thus the radio program from WOR is received between 6 and 7, the program from WJZ between 7 and 8, and returning to station WOR the program is received from that station 20 between 8 and 9.

Assume that the parts are in a neutral position as shown in Figures 7 and 7^a of the drawings, the operator sets the starting switch 75 so that the switch arm 71 is in engagement with 25 the contact 78 identified as the 6 o'clock contact, as 6 o'clock is the predetermined time which we have given as an example for the apparatus to operate. The apparatus is to operate continuously from 6 until 9, thus the switch arm 71 of the stop switch 76 is moved to engage the 9 o'clock contact 78 of the stop switch. These set positions are designated by dotted lines in Figures 7 and 7^a of the drawings. The operator next sets the switch arm 63 of the upper station control switch 56 identified as WOR and sets the switch arm 63 to engage the 6 o'clock contact 64. The upper control switch 56 identified as station WJZ, is next set so that the switch arm 63 of the said switch engages the 7 o'clock contact 64, after which the lower WOR switch 56 is set so that the switch arm 63 thereof engages the 8 o'clock contact 64 of the said switch. Thus the station selector switches are set for the successive operation of the apparatus to tune in stations WOR, WJZ, and returning to WOR. The switch 95 is manually actuated to close the negative lead in to the time control clock. As the hour hand 26 moves about the dial of the clock, the same will come in contact with the contact 28 identified as the 6 o'clock contact and on the exact minute of six o'clock the minute hand 25 engages the contact 29 identified as one of the fifteen minute period contacts, four of which have been shown at spaced intervals, whereby the minute hand engages one of the contacts 29 during each fifteen minute period. With the hour and minute hands in the position shown in dotted lines in Figure 7, the circuits are not closed until the second hand 21 makes contact with the contact segment 30 whereupon it distributes current to the line 31 from where it is picked up through the contact 28, minute hand 25, and thence out through the hour hand 26 and contact 28 which the hour hand engages. From the six o'clock contact 28, the circuit leads through wire 11 to the 6 o'clock wire consisting of one of the group of wires 68, thence through the proper wire 70 to the six o'clock contact 78 of the starting switch 75. The circuit continues through contact 78, contact arm 71, wire 87 to the electromagnet 86, through magnet 86 to wire 84 thence to wire 82 which is connected to the plus side of the current supply or to the lead in wire 80. Thus the circuit through the starting switch

energizes the electromagnet 86 drawing the switch arm 88 to a position to close the circuits leading to the radio receiver.

Simultaneously with the closing of the starting circuit, a station tuning circuit is closed, and which includes the hands of the clock hereinbefore mentioned, wire 11 to the respective wires 69, thence up through wire 68 connected to the six o'clock contact 64 of the upper WOR switch 56. From there the current passes through switch arm 63, wire 72 down to the selector contact member 51 identified as the station WOR selector. Assuming that the disk 42 is in the position shown in Figure 7^a, the current passes through the contact member 51 to the contact 44 on the disk 42 and thence through contact 49 to operate the relay R. After passing through the contact 49, the current passes through wire 104, and through the windings of the relay R, thence to wire 106, through the field 99 to wire 92 and thence to the positive lead in 90. This traces the circuit through the field of the motor, while the armature 33 receives its current in the following manner. When the relay R is energized, the switch arms 100 and 101 engage the terminal ends of the wires 105 and 106. After passing through the relay from the wire 105, the circuit extends up through wire 105, contact arm 100, wire 102, through armature 33, wire 103, switch arm 101, wire 106 to the wire 30 107 and thence through wire 92 to the positive lead in wire 90. This feed of current to the armature of the motor tends to rotate the same in order to turn the disk 42 in a counter-clockwise direction and the circuits remain closed until the gap 46 moves around to a point opposite the WOR selector finger 55 whereupon the circuits are broken and the motor ceases to operate. By reason of the arcuate contact 30, the circuits are maintained in closed position for a period of time just before the time for which the device is set to operate, and is maintained a sufficient length of time to enable the motor to operate in order to drive the disk 42 to the proper station finding position. It will of course be understood that the motor 32 drives the disk 42 through pinion 34, gear 35 and shaft 12, and that the tuning instruments for the tuning in of the particular radio stations are operable by reason of the rotation of the shaft 12. From the foregoing explanation, it will be seen that the circuits are broken as the hands of the clock move around the dial, but when the hour hand 26 reaches the seven o'clock contact 28, and the minute hand coacts with the hour hand to read seven o'clock, the circuits are again closed, but this time through the selective switch 56 identified as that for the tuning of station WJZ. The circuit is the same as previously explained for the tuning in of station WOR but due to the position of the disk 42, the contact member 51 associated with the WJZ switch is in engagement with the contact 48 which causes the current to flow to the armature of the motor in a reverse direction than that previously described. When 50 in this position, the circuit leads through contact member 51, contact 48 on the disk 42, contact 50, wire 108 to the relay S and through the coil of the relay to wire 105, from whence it passes down through the field 99, wire 107, wire 70 55 and thence out through the positive feed wire 80. The current to the armature 33 passes through wire 108 to wire 105 thence through wire 116, switch arm 112 which has been drawn over by the energizing of the coil of the relay S, 75

wire 110 through switch arm 101, wire 103 to the armature 33, thence through wire 102, switch arm 100, wire 109, switch arm 111, wire 114 to wire 106, thence to wire 107 and wires 92 and 90. Thus the direction of flow to the armature is reversed which in turn will rotate the disk 42 in a reverse direction to cause the gap 46 to move opposite the contact member 51 associated with the station WJZ, thus the circuits are broken and the tuning instruments of the receiver are set for the tuning in of station WJZ.

The program from station WJZ will be received until the minute and hour hands of the clock indicate eight o'clock, after which the circuit through the lowermost switch 56 which is arranged in parallel with the other switch associated with station WOR in order that the motor will be operated to return the instrument tuning shaft to a position to again tune in station WOR. The circuits for retuning in WOR after station WJZ has been heard is the same as previously described for the tuning in of this station, and a further explanation is not believed necessary.

When the hour and minute hands of the clock read 9 o'clock which is the time for which the apparatus is set to be shut off, the stop circuit is closed through the hands of the clock and contact 28 designated the nine o'clock contact, thence through the nine o'clock wire 71, wire 69 to which the wire 71 is connected, thence to the nine o'clock contact 78 of the stop switch 76 from where it passes through the switch arm 77, wire 89 to the electromagnet 88, thence out through wires 93, 92 and 90. The closing of the stop circuit energizes the electromagnet 88 causing the switch arm 98 to be drawn down out of engagement with the electromagnet 86, thus breaking the circuit to the radio receiver. Simultaneously with the shutting off of the switch 17, the electro-magnet 96 is energized through wire 89 through the coil of the electromagnet 96, thence out through the wire 92 to the positive lead wire 90. The circuit to the clock is broken when the apparatus is stopped as well as the switch 17 controlling the operation of the radio receiver.

With the parts shown in full lines in Figures 7 and 7^a of the drawings, the radio receiving set may be turned on and tuned in to any desired station independently of the automatic apparatus.

The automatic apparatus may also be operated independently of the time control feature, for by turning the switch arm 17 of the starting switch 75 so as to engage the contact 84, the circuit will be completed through the electromagnet 86 and the set turned "on." Likewise by moving the switch arm 17 of the stop switch into engagement with the contact 84 thereof, the electromagnet 88 may be energized and the switch arm 98 moved to an "off" position to shut off the radio receiver. Assuming that the set is turned "on" and it is desired to automatically tune in a selected radio broadcasting station. It is only necessary to turn the switch arm 63 of the selected radio selector switch to engage the contact 65, whereupon the station selector circuit will be operated to operate the tuning shaft 12 to the proper position. The only difference between the method of operation just described, and that in which the time control clock is arranged, is that the clock controls the time or interval during which the re-

ceiver is tuned in to a particular station, whereas without the use of the time control clock, the selector switches must be successively operated and not predeterminedly set for different timed intervals.

While I have shown and described what I deem to be the most desirable embodiment of my invention, I wish it to be understood that various other modifications may be resorted to if desired as come within the scope of the appended claims.

Having thus described the invention, what I claim as new and desire to secure by Letters Patent of the United States, is:—

1. An automatic control for radio receivers including a turnable instrument shaft adapted to be turned to predetermined radio station tuning positions, a rotor fixedly mounted on said shaft, a pair of spaced arcuate shaped contacts fixedly mounted on the periphery of said rotor with one of their ends in close proximity to each other, a pair of fixed opposed brush contacts respectively engaging said arcuate contacts, a plurality of spaced radio station finder contacts fixed relative to the axis of said shaft and adapted to engage the outer face of either of said arcuate contacts according to the radial position of rest of said rotor, an electric motor of the reversible driving type, driving means between said electric motor and said shaft, relay operated motor reversing circuits in which said motor, said finder contacts, and arcuate contacts are operatively arranged, said pair of opposed brush contacts being respectively arranged in the relay operated motor reversing circuit, and manually operated station control switches in the reversing circuits for closing either of the same depending upon the position of the arcuate contacts relative to the particular fixed contact through which the circuit is closed to cause said motor to operate said driving means until the rotor has been turned to a position whereupon the break between the spaced arcuate contacts radially aligns with the finger contact of a selected closed circuit to automatically open the same.

2. An automatic control for radio receivers including a turnable instrument shaft adapted to be turned to predetermined radio station tuning positions, a rotor fixedly mounted on said shaft, a pair of spaced arcuate shaped contacts fixedly mounted on said rotor with one of their ends in close proximity to each other, a plurality of spaced station finder contacts fixed relative to the axis of said shaft and adapted to engage either of said arcuate contacts according to the radial position of rest of said rotor, an electric motor, driving gear means between said electric motor and said shaft, circuit means in which said finder contacts and arcuate contacts are arranged, and manually operated switches in the respective circuits for selectively closing the same to cause said motor to operate until the rotor has been turned to a position whereupon the break between the spaced arcuate contacts radially aligns with the finger contact of a selected closed circuit to automatically open the same, and catch means engaging the teeth of one of the gears of said driving gear means for stopping said shaft to avoid over riding of said rotor upon automatic opening of a previously closed selected circuit.

ROBERT C. AVERY.
